UNITED STATES PATENT OFFICE.

DAVID S. STIMSON, OF CONCORD, NEW HAMPSHIRE.

DUST-GUARD FOR CAR-AXLE BOXES.

SPECIFICATION forming part of Letters Patent No. 351,944, dated November 2, 1886.

Application filed August 11, 1884. Serial No. 140,219. (No model.)

To all whom it may concern:

Be it known that I, DAVID S. STIMSON, a citizen of the United States, and a resident of Concord, in the county of Merrimac and State of New Hampshire, have invented a certain new and useful Improved Dust-Guard for Car-Axle Boxes, of which the following is a clear and exact description.

The object of my invention is to provide a dust-guard which is at once simple of construction, easy of application, and positive proof against the entrance of dust or other annoying influences.

In the accompanying drawings, forming part of this specification, in which similar letters of reference indicate corresponding parts in all the figures, Figure 1 shows a car-axle box in perspective having my improved dust-guard in position. Fig. 2 shows a section each of the dust-guard and the holding-frame, the former in position ready to be slipped into the latter, as when in position in the axle-box.

The axle-box A may be either the kind known as the "master car-builder's standard axle-box," or any other car-axle box serving the purposes of same, the inner end being provided with a chamber, B, known as the "dust-guard chamber." Slots *a* are formed on either side of the box opening into the dust-guard chamber, through which either section of the holding-frame C is inserted. This frame C is preferably formed of iron, and is adapted by reason of the grooves *c* to hold the dust-guard D, which is formed of some suitable wood, (whitewood is probably preferable,) and made of two sections, the inner ends of each being cut semicircular to fit over the axle, the outer ends being made rectangular, or nearly so—*i. e.*, the top and bottom sides being slightly tapered from the inner toward the outer end, for the purpose of facilitating the entrance of said dust-guard sections into the frames C C. These frames C C are provided with flanges C' at their outer ends, which rest against the sides of the axle-box, and extend above and below and on either side of the slots *a* in the axle-box, and thus close said openings, and prevent the entrance of dust to the dust-guard chamber.

Packing of any suitable elastic or flexible material may be inserted in grooves *c* on the inner faces of the flanges C', for the purpose of keeping a tight joint between said flanges and the axle-box.

To admit of the necessary vertical play of 55 the frame-sections C C and the dust-guard sections D D, the slots *a* in the axle-box A are made somewhat longer than is that part of the frame-sections C C which enters the same.

The frame-sections C C and dust-guard sections D D, when in their normal position, are separable or adapted to move apart in a horizontal direction, both being divided from their upper to their lower edge, preferably in a vertical line, and the meeting ends of the two sections of the frame C may be constructed with a tongue-and-groove or other suitable joint.

Steel springs E may be pivoted to the axle-box so as to bear against the outer ends of the frames C C or their flanges C' C', and thus hold 65 the dust guard at all times in direct contact with the axle.

This invention is unquestionably an improvement upon my United States Patent No. 298,253, dated May 6, 1884, inasmuch as the 75 flanges shutting over the slots in the axle-box in said patent are constructed upon the dust-guard itself and form part of the same, and must necessarily be thrown away when the dust-guard shall have worn sufficiently to 80 defeat its purposes; but when constructed in accordance with my improvements the said flanges are formed upon an iron frame made in sections, and designed to hold the sections of the dust-guard in position; hence the only 85 part to wear out is the dust-guard itself, which can be easily and cheaply replaced.

In Fig. 1 the lower part of one of the flanges C' is broken out sufficiently to show one of the slots *a* in the axle-box A.

Having thus described my invention, what I claim is—

The combination, with the axle-box A, having a dust-guard chamber, and the slots *a*, somewhat longer than the flanges C', of the 95 said flanges C', having groove *c*, the frames C, attached to the flanges and provided with guide-grooves *c*, and the dust-guards D, having horizontal play in the said guide-grooves, as set forth.

In testimony whereof I affix my signature in the presence of two witnesses.

DAVID S. STIMSON.
